(57) **CLAIM**

The ornamental design for a a toothpaste tube, shown and
described.

DESCRIPTION

The file of this patent contains at least one drawing/photograph
executed in color. Copies of this patent with color
drawing(s)/photograph(s) will be provided by the Office
upon request and payment of the necessary fee.

FIG. 1 is a perspective elevation view of a toothpaste tube;
FIG. 2 is a front view thereof;
FIG. 3 is a right side view thereof;
FIG. 4 is a back view thereof;
FIG. 5 is a left side view thereof;
FIG. 6 is a top view thereof; and
FIG. 7 is a bottom view thereof.

FIG. 8 is a perspective elevation view of a toothpaste tube;
FIG. 9 is a front view thereof;

FIG. 10 is a right side view thereof;
FIG. 11 is a back view thereof;
FIG. 12 is a left side view thereof;
FIG. 13 is a top view thereof; and
FIG. 14 is a bottom view thereof.

FIG. 15 is a perspective elevation view of a toothpaste tube;
FIG. 16 is a front view thereof;
FIG. 17 is a right side view thereof;
FIG. 18 is a back view thereof;
FIG. 19 is a left side view thereof;
FIG. 20 is a top view thereof; and
FIG. 21 is a bottom view thereof.

FIG. 22 is a perspective elevation view of a toothpaste tube;
FIG. 23 is a front view thereof;
FIG. 24 is a right side view thereof;
FIG. 25 is a back view thereof;
FIG. 26 is a left side view thereof;
FIG. 27 is a top view thereof; and
FIG. 28 is a bottom view thereof.

FIG. 29 is a perspective elevation view of a toothpaste tube;
FIG. 30 is a front view thereof;
FIG. 31 is a right side view thereof;

(Continued)

FIG. 32 is a back view thereof;
FIG. 33 is a left side view thereof;
FIG. 34 is a top view thereof; and
FIG. 35 is a bottom view thereof.
FIG. 36 is a perspective elevation view of a toothpaste tube;
FIG. 37 is a front view thereof;
FIG. 38 is a right side view thereof;
FIG. 39 is a back view thereof;
FIG. 40 is a left side view thereof;
FIG. 41 is a top view thereof; and,
FIG. 42 is a bottom view thereof.
Broken lines are used in the drawings to designate environmental structures or parts of a toothpaste tube that form no part of the claim.
